UNITED STATES PATENT OFFICE.

HARRY C. GRANT, OF BAYONNE, NEW JERSEY, ASSIGNOR TO KLAXON COMPANY, A CORPORATION OF DELAWARE.

MOTOR CONSTRUCTION FOR MECHANICAL HORNS.

Application filed May 3, 1922. Serial No. 558,163.

To all whom it may concern:

Be it known that I, HARRY C. GRANT, a citizen of the United States, and resident of Bayonne, in the county of Essex and State 5 of New Jersey, have invented certain new and useful Improvements in Motor Constructions for Mechanical Horns, of which the following is a specification.

My present invention is particularly de- 10 signed for use in connection with the motor construction invented by Duncan A. McConnell and set forth in his application Serial No. 558,108, filed May 3, 1922.

While certain details of my invention are 15 adapted for use in other relations, it primarily concerns a brush holder adapted for use in combination with a bridge piece which affords a front bearing for the armature shaft in such a motor. The nature and 20 objects of the invention will be more fully understood from the following description in connection with the accompanying drawings, in which—

Fig. 1 is a side elevation with the casing 25 broken away to show the operating parts of the instrument.

Fig. 2 is a section on the broken line 2—2, Fig. 1.

Referring to these drawings, the projector 30 1 is secured to front casing 2 by flange 3 and rib 4, and also by soldering or brazing, if desired. The rear casing is an integral drawn shell or cup comprising a cylindrical portion 5, rear end wall 6, and preferably 35 also, the diaphragm clamping flange 7 is integral. The diaphragm 8 is secured between the clamping members by screws 9, preferably passing loosely through the front casing 2 and secured by nuts 10 which may 40 be held from unscrewing by spring locking washers 11 of any known or desired type.

The rear wall 6 has a punched and drawn cylindrical extension 13 which constitutes a 45 housing for the bearing 14 which may be threaded therein and be secured by lock nut 15.

The shell 5, 6, is of iron or mild steel of such quality that it is capable of being punched and drawn to the shape shown in

the drawings and also capable of being utilized as the magnetic circuit between the pole pieces of the motor. The pole pieces are preferably located near the rear wall of the cup and there is a partition or bridge piece 51 across the cup near the open end thereof forming the front bearing for the armature shaft and this bridge piece is preferably of magnetic material forming part of the magnetic circuit of the motor field.

The peripheral wall is flattened in to form 60 an inwardly projecting boss 18 with a flat top 19 forming a good seat for the core pieces 20 and a flaring base as at 21. The outward flaring curvature of the boss away from the base of the core piece seems to make 65 the metal cup more nearly a magnetic unit with the cores, affording somewhat easier and natural lines of flow of the magnetic energy.

The electromagnets have soft iron cores 70 20, each having a reduced shank 23, whereby it is riveted into extremely intimate engagement with the surface 19 of one of the shell bosses. The cores are provided with the usual pole pieces, which may be integral 75 therewith or may be separate pieces rolled to shape and cut up, or they may be stamped directly from sheet metal. When the pole pieces are separately formed, they may be secured to the cores 20 by shanks, riveted 80 as at 24.

In practice the cores and pole pieces may have the magnetizing coils 25 mounted thereon and the shanks 23 inserted through the boss openings at 19. A cylindrical mandrel of the exact diameter required for the field of the motor may be then inserted with its axis exactly centered on the axis of the armature shaft bearing 14. The riveting operation is then performed preferably by 85 die presses acting simultaneously on both pole pieces so as to apply balanced thrust through the cores upon the intervening mandrel. The pressures required for riveting are sufficient to fit the metal of the case to 90 the diameter of the mandrel with great accuracy.

The motor armature 27, commutator 28,

and shaft 29, may be of the usual construction. The rear end of shaft 29 rests in the bearing 14. The forward bearing for shaft 29 is in transverse member, preferably of 5 magnetic material, which may be either a wall or merely a bridge piece 31, extending diametrically across the cup and secured in position by screws 32, screwing down on lock washers 33.

- 10 This bridge piece 31 carries the brush holders 34 which consist of blocks of insulating material, such as condensite or bakelite molded to shape under heat and pressure. Each has a square recess of suitable 15 depth and cross section to afford a sliding fit for the brushes 35 and parallel side flanges, which accurately fit against the sides of bridge piece 31. A convenient way of forming the recess for accurate sliding fit 20 of brushes 35 is to make one side wall 36 removable so that the recess may be molded as an open slot and the cover 36 afterwards applied and the whole secured by rivets 30, 30, extending through cover, brush holder 25 and bridge piece.

The circuit wire from the field coils is preferably twisted in the form of a helix as at 37, the length and diameter of the helix being such that it loosely fits the brush 30 holding recess. The axis of the helix is crosswise of the recess and is parallel with the axis of the commutator upon which the brush bears, consequently the surface of the helix forms a sort of rocker bearing 35 which affords a support across the width of the rear face of the brush. The surface of the helix being made of the round wires, bears upon the rear face of the brush at a multiplicity of points tending to slightly 40 wear and cut into the brush thereby maintaining and renewing perfect electric contact even under extreme adverse conditions, as where lubricating oil finds its way into the brush holder. The helix forms a head on the 45 end of the circuit wire, and the uncoiled or shank portion of the latter extends out through a relatively narrow slot 38, which latter need be only wide enough to permit easy passage and sliding fit of said circuit 50 wire. The helical contact head is resiliently forced against the base of the brush by means of the usual follower spring 39. If desired, the helix may be a tight coil with the sides of adjacent turns in contact, 55 and it may be dipped in solder or tinned to make it more rigid.

The parts may be assembled in the brush holders simply by removing the cover 36 and inserting them laterally in the position 60 shown. In most cases, however, it will be simpler to shift the commutator out of position, insert follower spring 39, insert the helix 37 with the circuit wire projecting through slot 38, insert the brush, force it 65 back to sufficiently compress the follower

spring, and finally insert the commutator in position between the ends of the brushes.

The diaphragm wear piece consists of a circular stamping having an eccentric portion projecting from one side thereof and 75 formed with a wear piece comprising an incline leading up to a more or less pronounced tip or edge which extends substantially radial to the axis of the wear piece, opposite to and parallel with the cam projections on the rotor 40. The rotor is preferably in the form of a hard steel cup as shown, and is secured in position by a stud screw 41 shown in dotted line, Fig. 1.

The wear piece is secured by a rivet 42 80 which extends through a square aperture 43 in the center of the diaphragm, through a cushion washer 44 which is preferably made of the same steel as the diaphragm, and through a front washer 45 which is preferably a cup shaped stamping as shown. The diaphragm is cushioned from contact with the metal clamping members by elastic washers 12, 12, preferably of cork composition.

I claim:

1. In a dynamo electric machine of the class described, a shell or cup of magnetic material and a bridge piece of magnetic material connecting opposite sides of the shell and affording a front bearing for the armature shaft and, on opposite sides of said bearing, aligned brush holders, each brush holder having a body portion molded from insulating material, formed with side flanges 95 embracing the side faces of said bridge 100 piece and tension members securing said brush holders to said bridge piece.

2. In a dynamo electric machine of the class described, a shell or cup of magnetic material and a bridge piece of magnetic material affording a front bearing for the armature shaft and, on opposite sides of said bearing, aligned brush holders, each brush holder having a body portion molded from insulating material, with the slideway in 105 the form of an open slot, a cover-piece of insulating material for said body portion and rivets extending through said cover and body portion and said bridge piece.

3. In a brush holder, a block of insulating material formed with a slideway having a brush and follower spring fitted therein, and formed with a lateral slot communicating with said slideway, in combination with a circuit connection comprising a conductor 110 projecting laterally through said slot and provided with a terminal head within said recess large enough to prevent withdrawal through said slot.

4. The combination specified by claim 3, 115 with the further feature that the enlarged head is located between the base of the brush and the follower spring.

5. The combination specified by claim 4, 120 with the further feature that the enlarged

head is cylindrical and arranged with its axis parallel with the axis of the surface of the brush which bears on the commutator.

6. The combination specified by claim 5, with the further feature that the cylindrical head presents circumferential ridges for engagement with the brush.

7. The combination specified by claim 5,

with the further feature that said head is located between the base of the brush and the follower spring and is formed as a helically coiled end of said conductor. 10

Signed at Bayonne, in the county of Essex and State of New Jersey, this 5th day of March, A. D. 1922.

HARRY C. GRANT.
